M. SIMSON

PROCESS OF MANUFACTURING FINGER RINGS AND RING FINDINGS

Filed Jan. 29, 1923

INVENTOR.

M. Simson.

BY

Richard D. Brown
ATTORNEY.

UNITED STATES PATENT OFFICE.

MAX SIMSON, OF NEW YORK, N. Y.

PROCESS OF MANUFACTURING FINGER RINGS AND RING FINDINGS.

Application filed January 29, 1923. Serial No. 615,710.

To all whom it may concern:

Be it known that I, MAX SIMSON, a citizen of the United States, residing at New York city, in the county of New York and State of New York, have invented certain new and useful Improvements in Processes of Manufacturing Finger Rings and Ring Findings, of which the following is a specification.

10 This invention relates to the process or method of manufacturing finger rings and ring findings and is particularly directed to the manner in which the gem mounting or crown is connected to the shank of the ring.

15 One of the objects of my invention is the method or process of manufacturing finger rings and the ring findings wherein the shank is undercut in such form as to receive a mounting or crown of any particular design and stamped or cut from a blank, the latter being soldered to the inner periphery of the shank so as to practically conceal the connection.

20 Another object of my invention is the process and method of manufacturing finger rings and ring findings wherein the gem mounting or crown may be stamped or cut from a single blank and shaped and designed according to a predetermined pattern including provision for receiving a gem setting, said mounting and setting being soldered to the flared ends of the shank of the ring and from the interior and constituting a support for the gem setting.

25 Another object of my invention resides in an article of manufacture consisting of a ring shank, a gem mounting or crown formed from a single blank and a gem setting wherein the soldered connection is invisible from the outer periphery of the shank and mounting.

30 In order to more clearly set forth the various steps resulting in the article of manufacture, reference is had to the accompanying drawings, wherein:

Figure 1 is a front view.

Figure 2 is a side view.

Figure 3 is a plan view.

Figure 4 is a plan with the gem setting removed.

Figure 5 is a front view of the ring shank.

Figure 6 is a view taken on the line 6—6 of Figure 5.

Figure 7 is a plan of the shank.

Figure 8 is a view taken on the line 8—8 of Figure 9.

Figure 9 is a plan of the gem mounting or crown.

Figure 10 is a plan of the gem setting.

Figure 11 is a view on the line 11—11 of Figure 10.

Figure 12 is a plan view of the gem mounting or crown blank.

Figure 13 is an end view.

Figure 14 is a side view showing the first bending operation of the blank.

Figure 15 is a plan showing the formation of the blank after the second bending thereof.

In order to more clearly understand the invention and the process of manufacturing the rings and findings, referring to the accompanying drawings, 5 designates the shank which consists of a malleable strip of metal, the ends 6, 7, of which are flat or beaten out preferably in a die, said ends gradually taper toward the top as indicated at 8 in Figure 2.

A shoulder 9 is thus formed when the shank is shaped to the size of the ring desired, said shoulder being on the inner periphery thereof forming the supporting surface for the gem mounting or crown now to be described.

A flat blank 10 of any desired shape is bent longitudinally and transversely at the center as indicated at 11, 12, so as to permit the blank to be formed and shaped to interfit between and beneath the flat portion 6, 7, of the shank above referred to. The length of the blank is substantially equal to the length of the flat portions above referred to, or in other words, of a length to extend from the shoulders 9 to the extreme ends of the shank. The central portion 13 of the blank is cut out in the form of an ellipse so that the sides may be bent toward each other. Since the blank is bent along the lines 11, 12, the sides will be curved outward as shown by Figure 15, the ends of the blank will be disposed downwardly so as to seat on the shoulders 9 and interfitting between the ends of the shank. Consequently, the ends of the shank will constitute two of the sides for the gem setting 14 soldered on the mounting.

After the blank has been bent to the desired shape and is fitted so as to properly seat on the shoulder 9, it is soldered thereto as indicated at 15 in such manner that the connection between the shank and the mounting is concealed from the outside periphery.

of the same. Usually the gem setting 14 is then soldered to the top of the mounting or blank 10 thus completing the process. The particular shape of the blank 10 or the gem setting 14 and the various designs that may be engraved, stamped, cut or otherwise made thereon, permits of a wide variation in the manufacture of a ring of this character by the above process but primarily, my invention resides in the formation of a mounting cut and shaped from a single blank so that it can interfit between the ends of a shank as above set forth.

I am aware of the fact that finger rings have been made wherein the gem mounting have been separately made and soldered on the outer periphery of the shank of the ring. This practice has been quite objectionable from a manufacturing standpoint because of the tedious work involved in fitting the parts, frequently resulting in the rejection of the rings upon inspection due to the soldering, which is quite noticeable.

Moreover, the shaping of the blank 10, which constitutes the mounting, according to my process, is such that an even and regular insert is had which may be made with accuracy and precision for the particular style of shank within which it is to be placed as clearly shown by the preferred form illustrated in the accompanying drawings.

Having thus described my invention, what I claim as new and desire to secure by United States Letters Patent is:—

35 1. The process of manufacturing rings which consists of forming a shank, cutting and shaping a single piece of metal and interfitting the shaped piece of metal between the ends of the shank and on the inner side thereof to form therewith a crown or gem setting.

2. The process of manufacturing rings which consists of forming a shank so that the free ends are of decreased thickness than 45 the body thereof, cutting and shaping a single piece of metal and interfitting the shaped piece of metal between the ends of

the shank and on the inner sides thereof to form therewith a crown or gem setting.

3. The process of manufacturing rings 50 which consists of forming a shank, flattening the ends of the shank to produce supporting shoulders in the inner peripheries thereof, cutting and shaping a single piece of metal and interfitting the shaped piece of metal between the ends of the shank and on the inner sides thereof to form a crown or gem setting, and soldering the shaped piece of metal on the shoulder.

4. The process of manufacturing rings 60 which consists of forming a shank, flattening the ends of the shank so that they taper outwardly from the body portion thereof, cutting and shaping a single piece of metal and interfitting the shaped piece of metal 65 between the ends of the shank and on the inner sides thereof to form therewith a crown or gem setting.

5. The process of manufacturing rings 70 which consists in forming a shank, flattening the ends of the shank to gradually taper outwardly producing supporting shoulders on the inner periphery thereof, bending a recessed polygonal blank along a line longitudinally and transversely of its center so that its sides are bowed outwardly and the ends of the blank disposed downwardly and interfitting the said shaped blank on the supporting shoulders of the shank.

6. The process of manufacturing rings 80 which consists in forming a shank, flattening the ends of the shank to produce supporting shoulders on the inner periphery thereof, bending a recessed polygonal blank along a line longitudinally and transversely of its center so that its sides are bowed outwardly and the ends of the blank disposed downwardly, interfitting the shaped blank 85 between the ends of the shank, soldering the said ends of the shaped blank to the supporting shoulders and soldering a gem setting on the top of the shaped blank.

In testimony whereof I affix my signature.
MAX SIMSON. [L. S.]
